UNITED STATES PATENT OFFICE.

EDWARD Z. LEWIS, OF CHICAGO, ILLINOIS, ASSIGNOR TO THE GENERAL MANIFOLD AND PRINTING COMPANY, OF FRANKLIN, PENNSYLVANIA, A CORPORATION OF PENNSYLVANIA.

MANIFOLDING SALESMAN'S CHECK.

972,551.

Specification of Letters Patent.

Patented Oct. 11, 1910.

Application filed February 3, 1910. Serial No. 541,813.

To all whom it may concern:

Be it known that I, EDWARD Z. LEWIS, a citizen of the United States, and a resident of Chicago, in the county of Cook and State of Illinois, have invented certain new and useful Improvements in Manifolding Salesmen's Checks; and I do hereby declare that the following is a full, clear, and exact description thereof, reference being had to the accompanying drawings, and to the letters of reference marked thereon, which form a part of this specification.

This invention relates to a multiform salesman's check and the object of the invention is to provide a check constructed in such a way that it is not only adapted for the production of the usual original and carbon copies of the same, but is also adapted to produce in inscribing the original bill an indestructible record of the bill which cannot be tampered with without detection and upon which will be reproduced whatever is written upon the original bill including any changes or alterations made thereon.

The invention, as shown and described herein, is applied to a check for meal service and more particularly to the checks used on dining cars. In said check form there is provided an original check upon which the order is written, two or more cook's checks underlying said original check, upon which carbon impressions are made of what is written on the bill, and a backer or card to which all of the parts are attached. Means are provided between the original check and the cook's checks to produce carbon impressions on the latter, and after the order is written on the original the carbon copy of the same is torn out and sent to the cook. In case additional orders are written there remains another cook's check or slip which will receive a carbon reproduction of what is added to the bill. After this is detached the total is written on the original which is reproduced on the card.

The invention relates specifically to the construction of the original check.

In the drawings:—Figure 1 shows my improved check with parts torn away or turned up to disclose the underlying sheets. Fig. 2 is a section through Fig. 1 on the line 2—2 thereof. Fig. 3 is a section through Fig. 1 on the line 3—3 thereof. Fig. 4 is a perspective view of the original check showing parts torn away. Fig. 5 is a plan view of

the original check before it has been folded into shape. Fig. 6 is a plan view of the first cook's check. Fig. 7 is a plan view of the second cook's check. Fig. 8 is a plan view of the card to which all of the checks are attached.

Referring now to that embodiment of my invention illustrated in the drawings, A is the original check as a whole, B, C, duplicate checks which are herein referred to as cook's checks, and D, the cardboard backer to which said several checks are attached. As illustrated in the drawings, each of the checks is printed as usual with any desired printed items and such other printed matter as is called for by the particular use to which the check is to be put.

The original check is folded from a strip of paper A¹, (see Fig. 5), which is in width equal to the height of the check, and in length, three times the width of said check. Said sheet is divided into three sections a¹, a², a³, which are separated from each other by means of lines of perforations x, y to permit of their ready folding in the manner presently to be described. Upon one side of the middle section a² of the sheet A¹ is printed the original check form A^x, and the rear side of said middle section is provided with a carbon surface, as indicated at A^y (see Fig. 4). Upon the reverse side of the section a¹, that is to say, on the side of the sheet A¹ opposite the side upon which the original check form appears, is printed a duplicate copy of the original check, as shown in dotted lines in Fig. 5, this form being arranged so that when the section a¹ is folded under the section a², the original check and the duplicate check will register with each other. The section a³ is provided with a carbon face on the same side of the sheet A¹ as is the original printed form A^x, as indicated at a⁴. The opposite side of said section is plain and unprinted.

In folding the sheet A¹ the section a¹ is folded under the section a² and the section a³ then folded so as to underlie the section a¹. All of the said sections are then permanently stitched together along the top and bottom of the printed form A^x, as indicated at a⁵, a⁶ (see Fig. 4). The original check A and the two duplicate checks B, C, are then secured to the card backer by means of staples as indicated at d, d, or in any other convenient manner.

It will be apparent that in the assembled 5 multiform check the carbon surface a^4 which is on the underside of the original check A, will in the first instance come in contact with the uppermost cook's check B and, after said 10 cook's check is detached, in contact with the one next underneath it, C, and that after this is torn out said carbon surface comes in contact with the card or backer D. The 15 cook's checks B, C, are provided near their tops with lines of perforations b, c (see Figs. 6 and 7) in order to provide for their ready detachment.

The card D is provided near its bottom 20 with a detachable section D¹ upon which is printed a punch-check D² printed with items of dollars and cents which corresponds to a similar punch-check D³ printed above the line of detachment. This detachable 25 check is used as a receipt for the purchaser and is punched at the total amount on the original check and indicates the total amount of the bill.

The total amount is not written upon the 30 bill, until the cook's checks have been used and detached, and as the original bill then rests on the card D with its carbon face in contact therewith the total written upon the original bill will be duplicated on the detachable punch-check D².

The advantages of my improved multiform salesman check are apparent from the above description. An unalterable record 35 of whatever is written on the original check is made on the duplicate section of the original check. It is absolutely impossible to get at this duplicate check section without either tearing the check along the stitching line or along the perforated lines at each 40 edge. The total amount appearing on the passenger's receipt check is also bound to agree with the total which appears on the duplicate check section.

It is obvious that the check may be variously modified without departing from the 45 spirit of the invention, and I do not wish to limit myself to the construction shown herein except as pointed out in the appended claims.

50 I claim as my invention:—

1. A manifolding salesman's check comprising, in combination with a suitable backer and one or more detachable duplicate check forms, a composite check consisting of 55 a single piece of paper folded to form an outer original check section, and an inner record check section, said sheet being folded to entirely inclose said record check section and being stitched permanently along the 60 top and bottom edges of the check with means located between said original check section and said record check section to produce a carbon copy on the latter, and means

interposed between said composite check as a whole and said duplicate checks to produce 65 carbon copies of said duplicate checks, together with means for securing all of the parts together.

2. A manifolding salesman's check comprising, in combination with a suitable 70 backer and one or more detachable duplicate check forms, a composite check and means for securing the several checks to said backer, said composite check consisting of a sheet of paper folded in sections, one of 75 said sections being an original check section on one side and having carbon reproducing material located on the other side, another check section being a record check section and having printed thereon on its reverse side 80 and in reverse position a form corresponding with the form on the original and being adapted to be folded under said original, and an inclosing check section adapted to underlie said record check section, together 85 with means for permanently securing said sections together along the top and bottom lines of the form, in combination with carbon means interposed between said composite check as a whole and said duplicate 90 checks.

3. A composite record check comprising a sheet of paper folded in three sections, one of said sections having printed on one side 95 an original form and having its opposite side provided with carbon material, a second section adapted to receive on its reverse side and in reverse position a duplicate record, said second section being folded under said original check section, and a 100 third section folded under said second named section, all three sections being stitched together along the top and bottom edges of the form.

4. A composite record check comprising a 105 sheet of paper folded in three sections, one of said sections comprising an outer, original check section, a second check section adapted to underlie said original check section and receive a duplicate record, means 110 interposed between said original check section and said record check section to produce a carbon copy on said record check section, and a third section adapted to underlie said 115 second named section, all three sections being stitched together along the top and bottom edges of the form.

In testimony, that I, claim the foregoing as my invention I affix my signature in the presence of two witnesses, this 1st day of 120 February A. D. 1910.

EDWARD Z. LEWIS.
